CLAIM

The ornamental design for an interface for a wrist watch pager, as shown.

DESCRIPTION

FIG. 1 is a front elevation view of an interface for a wrist watch pager showing our new design;

FIG. 2 is a top plan view thereof;

FIG. 3 is a right side elevation view thereof;

FIG. 4 is a rear elevation view thereof;

FIG. 5 is a bottom plan view thereof;

FIG. 6 is a left side elevation view thereof; and,

FIG. 7 is a top, left side, front perspective view thereof, on an enlarged scale.

FIG. 1

FIG. 2

FIG. 3

FIG.4

FIG.5

FIG.6

FIG. 7
